UNITED STATES PATENT OFFICE.

GEORGE C. CHASE, OF SOUTH ORANGE, NEW JERSEY, ASSIGNOR TO CHASE ADDING MACHINE CORPORATION, OF ORANGE, NEW JERSEY, A CORPORATION OF NEW JERSEY.

ADDING-MACHINE.

1,354,884.

Specification of Letters Patent.

Patented Oct. 5, 1920.

Application filed December 30, 1918. Serial No. 268,920.

To all whom it may concern:

Be it known that I, GEORGE C. CHASE, a citizen of the United States, resident of South Orange, in the county of Essex and

5 State of New Jersey, have made a certain new and useful Invention in Adding-Machines; and I declare the following to be a full, clear, and exact description of the same, such as will enable others skilled in the art 10 to which it appertains to make and use the invention, reference being had to the accompanying drawings, and to letters or figures of reference marked thereon, which form a part of this specification.

15 Figure 1 is a sectional view of the machine, on the line 1—1, Fig. 3.

Fig. 2 is front view, with parts removed and partly in section on the line 2—2, Fig. 1.

20 Fig. 3 is a detail section through the key board, on the line 3—3, Fig. 1.

Fig. 4 is a detail section through the numeral wheel shaft on the line 4—4, Fig. 2.

25 Fig. 5 is a diagrammatic view of the carrying devices, in position assumed when the lower order numeral wheel registers 9.

Fig. 6 is a similar view, the numeral wheel reading 2 and the latch engaging the frame.

Fig. 7 is a similar view, the numeral wheel reading 7 and the cam about to contact with 30 the carrying roller.

Fig. 8 is a similar view, the numeral wheel reading 7 and the higher order segment lever depressed.

Fig. 9 is a similar view, the numeral wheel 35 reading 9 and the higher order segment lever depressed.

Fig. 10 is a similar view, the numeral wheel reading 0 and the higher order segment lever in after-carry position.

40 Fig. 11 is a diagrammatic view of a segment lever and its denominational stop devices, in position assumed upon depression of a "five" key.

Fig. 12 is a similar view, with a "four" 45 key depressed.

Fig. 13 is a similar view, with a "three" key depressed.

Fig. 14 is a similar view, with a "two" key depressed.

50 Fig. 15 is a similar view, with a "one" key depressed.

Fig. 16 is a detail plan view of an inter-

mediate lever, with its attached latch lever, the frame member and stop lever appearing in section.

55

The invention relates to machines known as "double touch" adding machines or registers, provided with keys reading from 1 to 5, and wherein the larger digits are added by making two key strokes; 9, for instance, 60 being registered by successive depressions of a four key and a five key.

One object of the invention is to produce a machine having a light and short key stroke and a smooth working key tension.

65

Another object is to provide a simple and dependable construction for the purpose intended.

Another object is to avoid the use of two mechanisms for rotating a numeral wheel; one mechanism to register digital

70

values and the other to register carry values, thus simplifying the structure and operation and also avoiding the necessity for any and all controlling, delaying or guiding means

75

for preventing a loss of carry or other inaccuracy through interference of one mechanism with the other. Other objects and advantages will hereinafter appear.

It has been common in the key-operated multiple-order adding and calculating ma-

80

chine art to utilize a cam rotated by a numeral wheel for the purpose of transferring a carry from a lower order to a higher order wheel. Usually a roll, mounted upon a

85

spring-impelled transmitting member, bears against said cam and serves to transmit the motion to the next higher wheel. In order

to always insure the said roll of dropping to the lowest point of the cam under high-speed operation, and also to accomplish an

90

accurate transfer of the carry to a higher order wheel, in case it is at the time being operated by its own actuator, it has been necessary to delay the rotation of the carrying cam, by interposing a spring between the

95

numeral wheel and the cam and by providing controlling or delaying means.

In the present invention, the carrying cam is peculiarly adapted to the requirements of the "double touch" key arrangement, as

100

shown, having keys in value from 1 to 5. If the largest amount that may be added by any single key stroke is 5, whenever a carrying operation is initiated by a numeral wheel

that wheel cannot pass beyond its four position on that single stroke. I therefore provide the cam with no lift from the 0 to the 4 position, thereby admitting of the carrying 5 roll falling to its lowest position with relation to the cam immediately, or at any time after the key stroke has been made. Upon subsequent rotation of the said numeral wheel from the 4 position toward 9, the lift 10 of the cam will advance the carrying roll, and may store energy for another carrying operation.

Such a construction would not be practical in a machine provided with numeral keys to 15 register the higher digits, as 9, because the carrying cam would require, in adding the largest amount, or 9, an idle face from the 0 to the 8 position, leaving practically less than two points of lift on the cam, which 20 would involve such a sudden and heavy load on the numeral wheel as to render it difficult to operate, owing to a consequent building up of operating tension in the several columns from left to right across the machine, 25 thereby rendering the machine impractical.

Therefore, it will be seen that the "double touch" key arrangement, eliminating the higher digital keys, is in essential combination with the carrying cam arranged as in 30 my machine.

In the accompanying drawings, illustrating the invention, the numeral 2 designates depressible numeral keys in denominational series and having stems 3 and retracting 35 springs 4.

Related to each denominational series of keys is a depressible lever 5, pivoted in rear at 6 and at its forward end provided with a segment rack 7, engaging a pinion 8 carried 40 indirectly by a shaft 9, each lever having a retracting spring 10. Each key stem is provided with a shoulder 11, engaging the frame at 12 to limit its upward movement, and with a shoulder 13 engaging the related 45 segment lever in the depression of the key and actuating said lever to rotate the pinion 8.

For each denominational series of keys, selective stop means are provided, to check 50 the downward movement of each key of the series at a point below normal position just sufficient to provide for actuation of the segment lever and number wheel in accordance with the value of the key struck, this 55 means consisting preferably as follows:

Two rock levers, 14 and 15, are pivoted intermediately of their lengths at 16 to the framing below each segment lever, the latter being driven downwardly by the shoulders 60 18 of the key stems, and the rock levers having their forward and rear arms provided respectively with forward and rear upper stop faces *a*, *b*, *c* and *d*.

It is obvious that if either of the rock 65 levers has its forward and rear stop faces

contacting simultaneously with a segment lever moving downwardly, that the downward movement will be thereby stopped, and this is true of the 5 key and the related segment lever with respect to both of the rock 70 levers, as shown in Fig. 11, neither of the rock levers in this case being engaged by the key stem. It is also obvious that if either rock lever has its forward or rear arm engaged by a key stem moving downwardly, and is thereby rocked, that contact of the face of the opposite arm of the same rock lever with the lower edge of the segment lever will stop the downward movement of the latter. In this way, the 4 key 75 stem engages the rear arm of the rear rock lever, and the stop *a* of the forward arm of the latter contacts with the lower edge of the segment lever, as shown in Fig. 12, to limit the downward movement. Similarly, the 3 80 key stem engages the forward arm of the rear rock lever, and the stop *b* of the rear arm of the latter contacts with the segment lever to stop it, as in Fig. 13; the 2 key 85 stem engages the rear arm of the forward rock lever, and the stop *c* of the forward arm of the latter engages the segment lever to stop it, as in Fig. 14, and the 1 key stem 90 engages the forward arm of the forward rock lever, and the stop *d* of the rear arm 95 of the latter engages the segment lever to stop it, as in Fig. 15.

Numeral wheels 17 are loosely mounted upon the shaft 9, and means are provided to rotate any one of said wheels to the 100 proper extent, upon depression of a key of the denominational series related thereto, said means consisting, as shown, of a sleeve or hub 18, fast to each numeral wheel and loosely mounted upon the shaft 9, and upon 105 which in turn the pinion 8 is loosely mounted, a spring-pressed pawl 19 being pivoted to an extension 20 of the pinion and engaging the teeth of a ratchet wheel 21 carried by the sleeve 18, said sleeve at one end having fast thereto a wheel 22, having usually 110 20 teeth and termed an "escape wheel." Rotation of the pinion 8 will, through the pawl 19 and ratchet 21, rotate the sleeve 18 and the numeral wheel fast thereto, backward movement of the wheels being prevented by a spring-pressed pawl 23, engaging the ratchet 21 and pivoted at 24 to the framing.

When a key is depressed the pawl 19 slides 120 idly over the ratchet 21 during the downward stroke, and the numeral wheel remains stationary, being held by the backstop pawl 23, engaging the ratchet 21. During the upward stroke of the key the pawl 19 will 125 advance the ratchet 21 and the numeral wheel, said ratchet rotating beneath the backstop pawl.

If a numeral wheel stands at 0, and a key 130 related thereto, as the 4 key, for instance, is

depressed and released, 4 will appear as the numeral wheel reading. A 5 key in the same column being then depressed and released, the numeral wheel will be advanced 5 farther to 9. Any additions to the same numeral wheel will involve the transfer of 1 to the next higher numeral wheel, the mechanism for which will now be described.

Each numeral wheel, except the one of 10 highest order is provided with a carrying cam 25, rigidly driven thereby through a pin 26 of the wheel engaging a slot 27 of the cam, admitting of some slight play of the cam with respect to the wheel, for reasons hereinafter stated.

There is normally sufficient space between the shoulder 13 of a key stem and the upper edge of the related segment lever to admit of one extra step or degree of upward movement 20 of the segment lever, which extra movement may be termed the "actuator's carrying step". This extra upward movement of the segment lever takes place at the end of the ordinary upward movement 25 of said lever whenever there is carrying to be performed, and both the ordinary upward movement of the lever for rotating the numeral wheel to register digital values, and the extraordinary upward movement to 30 rotate the wheel to register a carry, are brought about through the influence of the same retracting spring 10 of said lever.

In the carrying operation each cam relates to a numeral wheel of lower order, and 35 the driving segment lever and the escape wheel relate to the numeral wheel of higher order.

Bridging or connecting each cam with each escape wheel is an escape lever 28, pivoted intermediately of its length at 29 to the related segment lever and engaging at 40 its forward end 30 with the aforesaid escape wheel; a "set lever" 31, pivoted intermediately of its length, at 32, to the framing 45 and having a downturned rear end 33 engaging the rear end 34 of the escape lever, and a "latch lever" 35, pivoted intermediately of its length, at 36, to the forward 50 upturned arm 37 of the set lever, said latch lever bearing at its upper end a roller 38, hereinafter referred to as the "latch roller" or "carrying roller", and with which the related cam aforesaid has engagement to accomplish the release of the escape lever from 55 the escape wheel at the proper time to effect a carry.

The latch lever has a rear extension 39 of its lower arm, said extension at its free end being provided with a lateral lug 40, engaging 60 in latched position with a lateral edge or corner 41 of a downturned portion 42 of the framing. The lower arm of the latch lever is provided with a lateral lug 43, and the rear extension of said lever is provided 65 with a lateral lug or stud 44 (shown as

rounded), these two last-named lugs being spaced apart to admit of some movement of the latch lever upon its pivot, and through contact respectively with opposite sides of the set lever, limiting this movement in both 70 directions.

The latch lever is held in latched engagement with the frame by a spring 45, attached at one end to the lower lug 43 and at the opposite end to the framing, this 75 spring acting to move the latch lever individually upon its pivot until said lug contacts with the forward arm of the set lever, and tending then to move the set lever to position with its rear end engaging with 80 the escape lever, as in latched position. This latch spring also in certain cases tends to actuate both the set lever and the latch lever as one part, upon the set lever fulcrum as a center, to move the carrying roller away 85 from the carrying cam. The latch spring is, however, inferior in strength to that of the escape lever spring (hereinafter referred to) and the segment lever retracting spring 10.

The latch lever or "latch" is, in one normal position thereof (Fig. 6), latched or engaged with the frame as stated; and in another normal position (Fig. 5) disengaged from the frame. Fig. 7 shows the parts in normal position, as in Fig. 6, the 90 cam being, however, moved to position about to contact with the carrying roller.

The parts being in the position shown in Fig. 5, in order to prevent an error by the accidental engagement of the latch lug 40 100 with the frame part 41, a stop arm 46 is provided, being pivoted at its upper end to the framing at 47, and having a spring connection 48 which tends to draw it toward and in contact with the lateral edge 41 of 105 the framing aforesaid. The lower end of this stop arm, when so engaged with the framing, projects slightly below the same or below the frame projection 42, for reasons hereinafter stated, and its spring 48 is 110 inferior in strength to that of the latch spring, admitting of the latter properly engaging the latch lug with the frame, against the resistance of the former spring. The stop arm is, however, not long enough to 115 contact with said latch lug when the latch is operated by the carrying roller riding the cam, at times when the driving segment lever of the next higher column is not depressed by its keys, as in Fig. 5. Therefore, 120 whenever the carrying roller passes over the high point of the cam, and the tail extension of the latch is depressed so that its stop lug or stud 44 engages the upper edge of the forward arm of the set lever, the stop 125 arm, through its spring, will move or drop over the latch lug 40, assuming the position shown in Fig. 5, thereby making it impossible for the latch to again engage the frame projection until after the carrying opera- 130

tion has been properly completed, as in Fig. 10.

It is not practical to manufacture the escape wheel with sufficient accuracy to admit of each tooth thereof arresting the escape lever precisely in the same position, and for this reason the framing is provided with a stop pin 49 for each escape lever, and engaging and arresting the latter when it is properly engaged with the teeth of the escape wheel.

It will be noted that the retracting spring of the segment lever, acting through the segment lever, escape lever, set lever, latch and carrying roller, will normally tend to move the carrying roller toward the carrying cam of the next lower wheel, the latch and set lever moving as one part, upon the set lever fulcrum as a center, and the stop 20 stud 44 of the tail extension of the latch engaging the forward arm of the set lever.

The latch lever may be either engaged with or disengaged from the frame when the segment lever is in normal position (shown as horizontal), the segment lever being held against rising above normal to carry, as in Fig. 6, by the bind of the latch upon the frame, thereby holding the forward arm of the set lever from moving downward to release the escape lever and the escape wheel, the tail arm of the set lever holding down the tail arm of the escape lever, against the tension of springs 10 and 50, owing to the set lever being fulcrumed to the framing.

In order to carry, a segment lever must move upwardly beyond its normal position, and this upward movement is normally prevented by engagement of the escape lever with the escape wheel and with the frame stop pin 49, and by engagement of tail arm of the locked set lever with the tail arm of the escape lever.

The latch lever, engaged with the frame as stated, has as its function to maintain the set lever in normal or locked position, holding down the tail arm of the escape lever to normally prevent a carry, unless, of course, the escape lever should be moved bodily downward with the segment lever, and should no carry follow such downward movement, the latch and frame engagement will still be effective to prevent any upward movement above normal of the tail arm of the set lever, that must take place in carrying.

The escape lever is provided, near the free end of its rear arm, with a spring 50, attached at one end to an upper extension 51 of the segment lever, this spring tending to withdraw the forward arm of the escape lever from engagement with the escape wheel, and being inferior in strength to that of the retracting spring 10 of the segment lever, and having no power to interfere with

the proper operation of the parts under the action of the said retracting spring 10.

The escape lever is also provided, near the free end of its rear arm, with an upper projection or "carrying position stop" 52, 70 normally spaced apart from and adapted to contact with the lower edge of the related segment lever, to limit the pivotal movement of the escape lever under the influence of its own spring 50, this individual pivotal movement of the escape lever taking place in the downward movement of the segment lever, as in Fig. 8, and also taking place in the upward movement of the segment lever beyond normal in carrying, as in Fig. 10. 75

When a segment lever is moved downward for digital value registration, as in Fig. 8, the escape lever will move downward bodily therewith, and the set lever will be moved pivotally by the latch spring until its rear arm contacts with a frame stop 53 to limit its downward movement, which is merely sufficient to admit of the carrying roller passing over the high point of the cam. And if the parts should be in the position last stated, and the digital value registration of a lower order wheel is made sufficient to (through the latch roller engagement with a high part of the cam) raise the forward or upper arm and depress the rear 90 or tail extension of the latch lever of the wheel of higher order, said latch lever will at the same time be released from the frame, as in Fig. 9.

When a segment lever is depressed for digital value registration, as in Fig. 8, the forward arm of the set lever being, through the latch spring 45, moved upwardly, the latch lever is moved bodily therewith to a slight extent, the lug 40 of its tail extension 105 being moved slightly away from the frame part 41, and the latch lever being moved bodily with the set lever, back to restore the latch and frame engagement and prevent a carry in the rise of the segment lever to normal position. 110

The escape lever being moved bodily downward with the segment lever, and no carry following, as the segment lever approaches normal position in its upward or return movement, the rear end of the escape lever will encounter the rear end of the locked set lever, the retracting spring 10 of the segment lever continuing to act and overcoming the escape lever spring, so that, 120 as the segment lever continues to travel upward to normal position, the escape lever will be moved upon its own pivot to reestablish the interval of separation of the "carrying position stop" 52 therefrom from the lower edge of the related segment lever, and to elongate or tension the escape lever spring and also to restore the engagement of the forward end of the escape lever with the escape wheel and frame stop pin, thereby 125 130

arresting the numeral wheel and arresting the segment lever at normal position, where it is held against the tension of its spring 10.

When a carry is to be effected, the high 5 part of the cam will have raised the latch lever at its forward or upper end, to release said lever from the frame, as in Fig. 5, and the highest point of the cam then passing from engagement with the carrying roller, 10 the escape lever spring will act to overcome the latch spring, and move the escape lever and the set lever, each upon its own pivot, the forward end of the escape lever dropping out of engagement with the escape 15 wheel, thereby releasing the segment lever, and the carrying roller moving toward the center of the carrying cam, and the latch spring being tensioned.

Normally, the carrying position stop of 20 the escape lever is spaced apart from the lower edge of the segment lever, as stated, said stop in the pivotal movement of the escape lever moving into contact with the segment lever, as in Fig. 10, and thereby 25 limiting the pivotal movement of the escape lever. This movement of the escape lever is immediately followed by an upward movement of the segment lever so released (and of the escape lever bodily therewith), under 30 the influence of the segment lever retracting spring 10, to restore the engagement of the escape lever with the escape wheel, the interval of release of the escape wheel being just sufficient to admit of its being rotated 35 one tooth through the said rise of the segment lever before the wheel is stopped by the reengagement of the escape lever therewith. And the escape lever so reengaged with the escape wheel will prevent further 40 rise of the segment lever.

In simplex or duplex operation, the segment lever of the higher order wheel in carrying moves upwardly from normal position, as in Fig. 10, and a key in the same 45 denominational series, or relating to the same segment lever, being depressed for digital value registration (no carry being released from the next lower wheel during said depression), the segment lever is moved 50 downwardly to and below normal position, and it is required that the latch shall be reengaged with the frame and that the segment lever in its return shall be stopped at normal position. To this end, as the segment lever moves downward, the escape lever moves downward therewith, and the 55 spring of the latch lever will act to move the set lever and the latch lever as one part, upon the set lever fulcrum as a center, the tail extension of the latch lever traveling 60 upon the lower arcuate surface 54 of the frame extension 42 (said surface struck from the set lever fulcrum as a center) and retaining the separation of its lower lug 43 65 from the lower edge of the forward arm of

the set lever until the rear or tail lug 40 of the latch is in position to be reengaged with the frame, when the latch spring will act to effect this reengagement, at the same time closing up the said separation or interval. In this operation the stop arm 46 will be moved backwardly from its position in Fig. 5, and its spring tensioned by the tail extension of the latch, just prior to the reengagement of the latch with the frame. 70 The latch, being now reengaged with the frame, will hold the set lever in normal position, ready to engage with the tail end of the escape lever as the latter rises again with the segment lever, and will stop the 80 segment lever at normal position.

In a case wherein a key in the same denominational series, relating to a segment lever in position after a carry, is not depressed, the cam upon the next lower order 85 wheel will effect this restoration of the segment lever to normal position before a new carry takes place, by lifting the latch lever, through engagement with the latch roller, the rear stud 44 of the latch lever taking a 90 bearing upon the upper edge of the forward arm of the set lever, and the latch lever and the set lever rotating as one part, upon the set lever fulcrum as a center, and when the high part of the cam is reached the restoration 95 will be complete, ready for a new carry, the tail arm of the escape lever being held down by the co-action of the latch roller upon the high part of the cam, and the rear stud 44 of the latch lever extension engaging 100 the upper edge of the forward arm of the set lever. In this operation the escape lever will pivot upon the frame stop pin 49.

In the restoration of a segment lever to 105 normal position from position assumed thereby after a carry has taken place, it is found necessary in practice that the segment lever shall be depressed slightly below its normal position, this additional depression being for the purpose of insuring the driving pawl 19 dropping properly into the teeth of the ratchet wheel 21 in reestablishing the driving connection between the segment lever and the numeral wheel. Each 110 cam is therefore provided with a slight additional rise 55, beyond its 9 part, thereby continuing to lift the latch roller and the latch lever as the numeral wheel passes from 9 to 0, and when said wheel shall have arrived at the 0 position the point of the cam 115 will have passed just sufficiently beneath the center of the latch roller to cause the curve of the roller, in its downward movement over the high point of the cam, to move the cam slightly forward of its proper position with relation to the numeral wheel, in order that said roller may be enabled to fall instantly to the low part of the cam when the highest part of the extension 55 has passed the radially aligned center of the 120

roll, to thereby admit of the carry, or of the "actuator's carrying step" aforesaid. The slot and pin connection of the cam and numeral wheel admit of this forward cam 5 movement.

As the latch roller starts to climb the cam again, it will push the cam slightly backward to its proper relative position, the pin of the numeral wheel moving to normal or 10 driving position in the slot of the cam. It will be noted here that the relative movement between the numeral wheel and the carrying cam must be insufficient to allow the high part of the cam to pass beneath the center 15 of the carrying roller in case the numeral wheel is arrested in the 9 position and the carrying cam advances with relation to the numeral wheel because of its own momentum.

20 In duplex operation, or in cases where denominational keys of different columns are operated with overlapping strokes, it is necessary that the carry shall still be properly effected. Take the positions of the 25 parts in Fig. 8, for instance, where a higher order key or segment lever is shown as depressed for digital value registration, a depression of a lower order key being simultaneous, or following immediately, and the 30 carry being required to be effected, the cam in its rotation will trip the latch lever from its frame engagement, as in Fig. 9, and admit of the subsequent upward movement beyond normal of the rear arm of the set lever, 35 and will admit of the escape lever remaining released from the escape wheel until the carry is completed. The latch being then tripped, as stated in reference to Fig. 9, the stop arm 46 will at once be moved by its 40 spring to position over the tail extension of the latch lever, and will prevent the latter from being reengaged with the frame while the two segment levers are being depressed and the digital value rotation of the related 45 numeral wheel is taking place, and also while the high point of the cam is passing from engagement with the latch roller and after it has passed from such engagement, until the digital value rotation of the 50 numeral wheel is completed; the rotation of the numeral wheel for the carry following immediately, not upon account of any delay of the carry mechanism, but merely because the segment lever is rotating the numeral 55 wheel for a digital value registration, and cannot therefore simultaneously rotate the numeral wheel to register a carry.

And if, in the case stated, the latch relating to a higher order wheel shall be already 60 in tripped position, the stop arm 46 will be already located over the tail extension of the latch lever, as in Fig. 9, and will in the same way and for the same reasons hold the latch lever from being reengaged with the frame 65 while the two segment levers are depressed.

It will be noted that the escape lever will engage with the escape wheel at the end of a digital value rotation of a numeral wheel, to prevent the latter from running ahead by momentum, and thereby causing an error. 70

The after-carry position of the segment lever is a position of rest, and is, with any other position of rest, equally to be regarded as a normal position, although the substantially horizontal position of the segment 75 lever is referred to for convenience as normal position.

I claim:

1. In a register, numeral wheels, and an actuating means operable to impart to its 80 respective wheel movement to register digital values and movement to register a carry, including a prime mover and means including a cam rigidly driven from each wheel for restoring the prime mover from position after 85 a carry to normal position.

2. In a register, numeral wheels, and an actuating means operable to impart to its 90 respective wheel movement to register digital values and movement to register a carry, including a prime mover and carry-tripping means operable also to restore a prime mover from position after a carry to normal position.

3. In a register, numeral wheels, and an 95 actuating means operable to impart to its respective wheel movement to register digital values and movement to register a carry, including a prime mover and carry tripping means including a cam driven from each 100 wheel and operable also to restore a prime mover from position after a carry to normal position.

4. In a register, numeral wheels, and a 105 spring actuator operable to impart to its respective wheel movement to register digital values and movement to register a carry, and including carry tripping means operable also to retension the actuator.

5. In a register, numeral wheels, and an 110 actuating means operable to impart to its respective wheel movement to register digital values and movement to register a carry, including a spring lever and carry tripping means operable also to restore the spring 115 lever from position after a carry to normal position and to retension the lever.

6. In a register, numeral wheels, and an actuating means operable to impart to its 120 respective wheel movement to register digital values and movement to register a carry, including a prime mover and carry tripping means embodying a cam driven from each wheel operable also to restore a prime mover from position after a carry to normal 125 position.

7. In a register, numeral wheels, and a carry mechanism including an actuator operable to impart to its respective wheel movement to register digital values and 130

movement to register a carry, and also including means individual to each wheel for restoring the carrying power of said actuator.

5 8. In a register, numeral wheels, and a carry mechanism for each wheel and including a spring actuator operable to impart to its respective wheel movement to register digital values and movement to register a 10 carry, and carry tripping means operable to restore the actuator from position after a carry to normal position and to retension the actuator.

9. In a register, numeral wheels, and a 15 carry mechanism for each wheel and including a spring actuator operable to impart to its respective wheel movement to register digital values and movement to register a carry, and carry tripping means including 20 a cam driven from each wheel and operable to restore the actuator from position after a carry to normal position and to retension the actuator.

10. In a register, numeral wheels, a spring 25 actuator for operating a numeral wheel to register digital values, and connecting means between the next lower numeral wheel and the actuator, operable by the former to tension and to release, said actuator to register 30 carry values.

11. In a register, numeral wheels, a spring actuator for operating a numeral wheel to register digital values, and connecting means between the next lower numeral 35 wheel and the actuator, operable by the former and including a cam driven from said lower wheel to tension and to release said actuator to register carry values.

12. In a register, numeral wheels, an actuator for operating a numeral wheel to register digital values, and connecting means between the next lower numeral wheel and the actuator, operable by the former and including an escape wheel and an escape 45 device carried by the actuator and engaging the escape wheel, said actuator being adapted and operated by the connecting means to register carry values.

13. In a register, numeral wheels, an actuator for operating a numeral wheel to register digital values, and connecting means between the next lower numeral wheel and the actuator, operable by the former and holding the actuator at normal position, including an escape wheel and an escape device carried by the actuator and engaging the escape wheel, said actuator being adapted and released by the connecting means to register carry values.

60 14. In a register, numeral wheels, an actuator for operating a numeral wheel to register digital values, and connecting means between the next lower numeral wheel and the actuator, operable by the former and including an escape wheel, an escape lever

carried by the actuator and engaging the escape wheel, a cam driven from said lower wheel, and an intermediate lever operated by the cam and engaging the escape lever, said actuator being adapted and operated 70 by said connecting means to register carry values.

15. In a register, numeral wheels, an actuator for operating a numeral wheel to register digital values, and connecting means 75 between the next lower numeral wheel and the actuator, operable by the former and holding the actuator at normal position, including an escape wheel, an escape lever carried by the actuator and engaging the 80 escape wheel, a cam driven from said lower wheel, and an intermediate lever operated by the cam and engaging the escape lever, said actuator being adapted and released by said connecting means to register carry 85 values.

16. In a register, numeral wheels, a spring actuator for operating a numeral wheel to register digital values, and connecting means between the next lower numeral 90 wheel and the actuator, operable by the former and holding the actuator at normal position, including an escape wheel and an escape device engaging the escape wheel, said actuator being adapted and released by 95 said connecting means to register carry values, and said connecting means being adapted to restore and retension the actuator.

17. In a register, numeral wheels, a spring 100 actuator for operating a numeral wheel to register digital values, and connecting means between the next lower numeral wheel and the actuator, operable by the former and holding the actuator at normal 105 position, including an escape wheel, an escape device engaging the escape wheel, and a cam driven from said lower wheel, said actuator being adapted and released by said connecting means to register carry values, 110 and said connecting means being adapted to restore and retension the actuator.

18. In a register, numeral wheels, a spring actuator for operating a numeral wheel to register digital values, and connecting means 115 between the next lower numeral wheel and the actuator, operable by the former and holding the actuator at normal position, including an escape wheel and an escape device carried by the actuator and engaging 120 the escape wheel, said actuator being adapted and released by said connecting means to register carry values, and said connecting means being adapted to restore and retension the actuator.

19. In a register, numeral wheels, a spring actuator for operating a numeral wheel to register digital values, and connecting means between the next lower numeral wheel and the actuator, operable by the former and 130

holding the actuator at normal position, including an escape wheel, an escape lever carried by the actuator and engaging the escape wheel, a cam driven from said lower wheel, and an intermediate lever operable by the cam and engaging the escape lever, said actuator being adapted and released by said connecting means to register carry values, and said connecting means being adapted to restore and retension the actuator.

20. In a register, numeral wheels, denominational keys, a spring actuator for operating a numeral wheel to register digital values, and connecting means between the next lower numeral wheel and the actuator, operable by the former and holding the actuator at normal position, including an escape wheel and an escape device engaging the escape wheel, said actuator being adapted and released by said connecting means to register carry values and said connecting means being adapted and operable by a denominational key to restore and retension the actuator.

21. In a register, numeral wheels, and a carry mechanism for each wheel and including an actuator lever operable to impart to its respective wheel movement to register digital values and movement to register a carry, an escape wheel, and an escape device carried by the actuator lever and engaging the escape wheel.

22. In a register, numeral wheels, and a carry mechanism for each wheel and including an actuator operable to impart to its respective wheel movement to register digital values and movement to register a carry, an escape wheel, an escape device engaging the escape wheel, an intermediate lever engaging the escape device, and a cam driven from the next lower numeral wheel and engaging the intermediate lever.

23. In a register, numeral wheels, and a carry mechanism for each wheel and including an actuator lever operable to impart to its respective wheel movement to register digital values and movement to register a carry, an escape wheel, an escape lever carried by the actuator lever and engaging the escape wheel, a cam driven from the next lower numeral wheel, and an intermediate lever operable by the cam and engaging the escape lever.

24. In a register, numeral wheels, denominational keys, and an actuator operable to impart to its respective wheel movement to register digital values and movement to register a carry, said actuator being adapted to be restored to normal from after-carry position step by step during successive strokes of a denominational key or keys.

25. In a register, the combination of a series of denominational numeral wheels

movable from normal position to carry, a series of actuators for said wheels, series of keys, each actuator being adapted to be partially restored to normal from after-carry position during the stroke of a lower order key, a key related to said actuator being capable of completing the restoration.

26. In a register, numeral wheels, actuator levers therefor movable from normal position to carry, and means including a lever fulcrumed to the machine frame and a cam driven from a numeral wheel for restoring an actuator lever to normal position after a carry.

27. In a register, numeral wheels, actuator levers therefor movable from normal position to carry, and means including an escape wheel for each numeral wheel, an escape device engaging the escape wheel, and a lever fulcrumed to the machine frame and engaging the escape device for restoring an actuator lever to normal position after a carry.

28. In a register, numeral wheels, actuator levers therefor movable from normal position to carry, and means including an escape wheel for each numeral wheel, an escape lever carried by each actuator lever and engaging the escape wheel, and a lever fulcrumed to the machine frame and engaging the escape lever for restoring an actuator lever to normal position after a carry.

29. In a register, numeral wheels, actuator levers therefor movable from normal position to carry, and means including an escape wheel, a cam driven from a numeral wheel, a lever fulcrumed to the machine frame, and an escape lever engaging the escape wheel for restoring an actuator lever to normal position after a carry.

30. In a register, numeral wheels, actuator levers therefor movable from normal position to carry, and means including an escape wheel, a cam driven from a numeral wheel, a lever fulcrumed to the machine frame, and an escape lever carried by the actuator lever for restoring an actuator lever to normal position after a carry.

31. In a register, numeral wheels, and carrying mechanism including a spring-imelled actuator lever for each wheel, an escape wheel, an escape lever engaging the escape wheel and carried by and having a releasing spring connected to the actuator lever, a lever fulcrumed to the machine frame and engaging the escape lever, and a cam driven from a numeral wheel and operating the intermediate lever to restore the escape and actuator levers to normal position and to tension the same after a carry.

32. In a register, numeral wheels, actuator levers therefor movable from normal position to carry, and means including an escape wheel and an escape device engaging

the escape wheel for restoring an actuator lever to normal position after a carry, said device operable also to release and to check the numeral wheel.

- 5 33. In a register, numeral wheels, actuator levers therefor movable from normal position to carry, and means including an escape wheel, an escape device engaging the escape wheel and a cam driven from a numeral wheel and governing said escape device for restoring an actuator lever to normal position after a carry, said device operable also to release and to check the numeral wheel.
- 10 34. In a register, numeral wheels, actuator levers therefor movable from normal position to carry, and means including an escape wheel and an escape device carried by each actuator lever and engaging the escape wheel for restoring the actuator lever to normal position after a carry, said device operable also to release and to check the numeral wheel.

15 35. In a register, numeral wheels, actuator levers therefor movable from normal position to carry, and means including an escape wheel for each numeral wheel, an escape device carried by each actuator lever and engaging the escape wheel, and a cam driven from the numeral wheel of lower order and governing said escape device for restoring the actuator lever to normal position after a carry, said device operable also to release and to check the numeral wheel.

20 36. In a register, numeral wheels, denominational keys, an actuator operable to impart to its respective wheel movement to register digital values and movement to register a carry and including means for restoring the actuator to normal from after-carry position during the entire operative stroke of a denominational key.

25 37. In a register, numeral wheels, denominational keys in series, an actuator operable to impart to its respective wheel movement to register digital values and movement to register a carry and including means for restoring the actuator to normal from after-carry position during the entire operative stroke of any denominational key of a series:

30 38. In a register, numeral wheels, denominational keys, a spring actuator operable upon its return stroke to impart to its respective wheel movement to register digital values and movement to register a carry and including means for restoring the actuator to normal from after-carry position during the return stroke of a denominational key.

35 39. In a register, numeral wheels, denominational keys, a spring actuator operable upon its return stroke to impart to its respective wheel movement to register digital values and movement to register a carry

and including means for restoring the actuator to normal from after-carry position during the entire return stroke of a denominational key.

40. In a register, numeral wheels, denominational keys, and an actuator operable to impart to its respective wheel movement to register digital values and movement to register a carry and including connecting means between the next lower wheel and the actuator, operable by the former to restore the actuator to normal from after-carry position during the entire operative stroke of a denominational key.

41. In a register, numeral wheels, denominational keys, and a spring actuator operable upon its return stroke to impart to its respective wheel movement to register digital values and movement to register a carry and including connecting means between the next lower numeral wheel and the actuator, operable by the former to restore the actuator to normal from after-carry position during the entire return stroke of a denominational key.

42. In a register, numeral wheels, an actuator lever, and connecting means between the next lower wheel and the actuator lever, operable by the former and including an escape wheel and an escape lever carried by the actuator lever and engaging the escape wheel for restoring the actuator lever to normal from after-carry position.

43. In a register, numeral wheels, an actuator movable from normal position to carry, and connecting means between the next lower wheel and the actuator, operable by the former and including an escape wheel and an escape device engaging the escape wheel, for restoring the actuator to normal from after-carry position, said device operable also to release and to check the numeral wheel.

44. In a register, numeral wheels, an actuator lever, movable from normal position to carry, and connecting means between the next lower wheel and the actuator lever, including an escape wheel, an escape lever carried by the actuator lever and engaging the escape wheel, an intermediate lever engaging the escape lever, and a cam driven from the numeral wheel and engaging the intermediate lever, for restoring the actuator lever to normal from after-carry position, said escape lever operable also to release and to check the numeral wheel.

45. In a register, numeral wheels, an actuator movable from normal position to carry, and connecting means between the next lower wheel and the actuator, including an escape wheel, an escape device engaging the escape wheel, an intermediate lever engaging the escape device, and a cam driven from the numeral wheel and en-

gaging the intermediate lever, for restoring the actuator to normal from after-carry position, said device operable also to release and to check the numeral wheel.

5 46. In a register, numeral wheels, an actuator lever movable from normal position to carry, a frame member, and connecting means between the next lower wheel and the actuator lever, operable by the former and including an escape wheel, and an escape lever carried by the actuator lever, engaging the escape wheel and having a pivotal bearing upon said frame member for restoring the actuator lever to normal from 10 after-carry position, said escape lever operable also to release and to check the numeral wheel.

15 47. In a register, numeral wheels, an actuator movable from normal position to carry, a frame member, and connecting means between the next lower wheel and the actuator, operable by the former and including an escape wheel and an escape device engaging the escape wheel and having 20 a pivotal bearing upon said frame member for restoring the actuator to normal from after-carry position, said device operable also to release and to check the numeral wheel.

25 48. In a register, numeral wheels, an actuator, movable from normal position to carry, a frame member, and connecting means between the next lower wheel and the actuator, operable by the former and including 30 a lever having a pivotal bearing upon said frame member for restoring the actuator to normal from after-carrying position.

35 49. In a register, numeral wheels, and carry mechanism including spring actuators 40 for rotating said wheels, means for holding said actuators tensioned to carry, and a cam driven from each wheel for releasing the holding means, the cam and the holding means operable also to retension the actuator.

45 50. In a register, numeral wheels, and carry mechanism including spring levers for rotating said wheels, means for holding said levers tensioned to carry including an 50 element releasably engaging the machine frame and a cam driven from each wheel for releasing the element from the frame, the cam and the holding means operable also to retension the actuator.

55 51. In a register, numeral wheels, and carry-controlling means including a cam having driving connection with each wheel through the medium of a slot and pin, and a coöperating member riding the cam, and 60 serving upon release from the high part thereof to release a carry, said member adapted as it passes over the high part of the cam to push the cam forwardly with relation to the wheel to permit of an earlier

release of said member with a lesser relative movement of the numeral wheel.

52. In a register, numeral wheels, and carry-controlling means including a cam having driving connection with each wheel through the medium of a slot and pin, and 70 a coöperating member riding the cam and serving upon release from the high part thereof to release a carry, said member adapted as it passes over the high part of the cam to push the cam forwardly with 75 relation to the wheel, and thereafter to push the cam backwardly with relation to said wheel to normal position.

53. In a register, numeral wheels, a spring-retracted actuator lever for each 80 wheel having a ratchet and pawl driving connection therewith, and means for restoring the actuator lever to normal position from position after a carry, including a cam having driving connection with each 85 wheel through the medium of a slot and pin, and a coöperating member riding the cam and serving upon release from the high part thereof to release a carry, said cam adapted to impart additional movement to said member as the related numeral wheel passes from 9 to 0 position, to insure proper engagement of the pawl with the ratchet of said drive connection, and said coöperating member adapted as it passes 95 over the high part of the cam to push the cam forwardly with relation to the wheel.

54. In a key-operated adding machine, a series of denominational numeral wheels, a series of column actuators operating said 100 wheels, a series of digital keys for each actuator and wherein the smaller digits only are represented, and a carry-controlling cam having a rigid driving connection with each wheel, said cam having no lift or being concentric with its shaft approximately 105 from the 0 position to the 4 position thereof.

55. In a key-operated adding machine, a series of denominational numeral wheels, a series of column actuators operating said 110 wheels and including carrying springs, a series of digital keys for each actuator and wherein the smaller digits only are represented, and means for tensioning each spring actuator including a cam rigidly 115 driven from a numeral wheel, said cam having no lift or being concentric with its shaft approximately from the 0 position to the 4 position thereof.

56. In a register, numeral wheels, and means for checking each wheel at the end of its digital value registering movement, including a carrying cam related to the next lower numeral wheel, and a wheel-arresting member governed by the position of said 125 cam.

57. In a register, numerals wheels, and means for checking each wheel at the end

of its digital value registering movement, including a carrying cam related to the next lower numeral wheel, a lever fulcrumed to the machine frame and engaging said cam, and a wheel-arresting member engaging said lever.

58. In a register, numeral wheels, and means for checking each wheel at the end of its digital value registering movement, including an actuator lever for the wheel, an escape wheel, an escape lever carried by the actuator lever and adapted to engage the escape wheel, and a carrying cam related to the next lower numeral wheel and governing the action of said escape lever.

59. In a register, numeral wheels, and means for checking each wheel at the end of its digital value registering movement, including an escape wheel, an actuator lever, a carrying cam related to the next lower numeral wheel, a lever fulcrumed to the machine frame and engaging said cam, and an escape lever carried by the actuator lever, engaging said first-named lever and adapted to engage the escape wheel.

60. In a register, numeral wheels, and means for checking each wheel at the end of its registering movement, including an element releasably engaging the machine frame, and means for releasing said element from the frame in the carrying operation.

61. In a register, numeral wheels, and means for checking each wheel at the end of its registering movement, including an intermediate lever fulcrumed to the machine frame and a latch lever carried by the intermediate lever and releasably engaging said frame, and means for releasing the latch lever from the frame in the carrying operation.

62. In a register, numeral wheels, and means for checking each wheel at the end of its registering movement, including an escape wheel, an element releasably engaging the machine frame, an escape lever adapted to engage the escape wheel, and means for releasing said element from the frame in the carrying operation.

63. In a register, numeral wheels, and means for checking each wheel at the end of its registering movement, including an escape wheel, an actuator lever, an element releasably engaging the machine frame, an escape lever carried by the actuator lever and adapted to engage the escape wheel, and means for releasing said element from the frame in the carrying operation.

64. In a register, numeral wheels, and means for checking each wheel at the end of its registering movement, including an escape wheel, an intermediate lever fulcrumed to the machine frame, a latch lever carried by the intermediate lever and releasably engaging the machine frame, an

escape lever adapted to engage the escape wheel, and means for releasing said latch lever from the frame in the carrying operation.

65. In a register, numeral wheels, and means for checking each wheel at the end of its registering movement, including an actuator lever, an escape wheel for each numeral wheel, an intermediate lever fulcrumed to the machine frame, a latch lever carried by the intermediate lever and releasably engaging said frame, and an escape lever carried by the actuator lever and adapted to engage the escape wheel, and means for releasing the latch lever from the frame in the carrying operation.

66. In a register, numeral wheels, and means for checking each wheel at the end of its movement to register digital values, including an actuator lever, an escape wheel, an intermediate lever, a latch lever carried by the intermediate lever and releasably engaging the machine frame, and an escape lever carried by the actuator lever and adapted to engage the escape wheel, and a cam driven from a numeral wheel of lower order and acting to release the latch lever from the frame in the carrying operation, said cam, said latch lever so released and said intermediate lever being adapted to check the higher order numeral wheel at the end of its movement to register digital values.

67. In a register, numeral wheels, and carry-tripping means including an escape wheel for each numeral wheel, an escape device engaging the escape wheel, an element releasably engaging the machine frame and controlling said escape device, and means for releasing said element from the frame to thereby release the engagement of the escape device.

68. In a register, numeral wheels, and carry-tripping means including an escape wheel for each numeral wheel, an escape device engaging the escape wheel and having a releasing spring, an element releasably engaging the machine frame and thereby holding the escape device tensioned, and means for releasing said element from the frame to thereby release the engagement of the escape device.

69. In a register, numeral wheels, and carry-tripping means including an escape wheel for each numeral wheel, an escape device engaging the escape wheel and having a releasing spring, an element releasably engaging the machine frame and thereby holding the escape device tensioned, and means including a cam driven from a numeral wheel for releasing said element from the frame to thereby release the engagement of the escape device.

70. In a register, numeral wheels, and

carry-tripping means including an escape wheel for each numeral wheel, an escape lever engaging the escape wheel and having a releasing spring, means for holding the escape lever tensioned, including an intermediate lever engaging the escape lever and a latch lever fulcrumed to the intermediate lever and releasably engaging the machine frame, and means for releasing the latch lever from the frame.

71. In a register, numeral wheels, and carry-tripping means including an escape wheel for each numeral wheel, an escape lever engaging the escape wheel and having a releasing spring, means for holding the escape lever tensioned, including an intermediate lever fulcrumed to the machine frame and engaging the escape lever, and a latch lever fulcrumed to the intermediate lever and releasably engaging the machine frame, and means for releasing the latch lever from the frame including a cam driven from a numeral wheel.

72. In a register, numeral wheels, and carry-tripping means including an escape wheel for each numeral wheel, wheel actuator levers, an escape device carried by each actuator lever and engaging the escape wheel, an element releasably engaging the machine frame and controlling said escape device, and means for releasing said element from the frame.

73. In a register, numeral wheels, and carry-tripping means including an escape wheel for each numeral wheel, wheel-actuator levers, an escape device carried by each actuator lever and engaging the escape wheel, an element releasably engaging the machine frame and controlling said escape device, and means including a cam driven from a numeral wheel for releasing said element from the frame.

74. In a register, numeral wheels, and carry-tripping means including an escape wheel for each numeral wheel, wheel-actuator levers, an escape lever carried by each actuator lever and engaging the escape wheel, an intermediate lever fulcrumed to the machine frame and engaging the escape lever, a latch lever fulcrumed to the intermediate lever and releasably engaging the machine frame, and means for releasing said latch lever from the frame.

75. In a register, numeral wheels, and carry-tripping means including an escape wheel for each numeral wheel, wheel-actuator levers, an escape lever carried by each actuator lever and engaging the escape wheel, an intermediate lever fulcrumed to the machine frame and engaging the escape lever, a latch lever fulcrumed to the intermediate lever and releasably engaging the machine frame, and means including a cam driven from a numeral wheel for releasing the latch lever from the frame.

76. In a register, numeral wheels, and carry-tripping means including spring-impelled wheel-actuator levers, an escape wheel for each numeral wheel, an escape lever engaging the escape wheel and carried by and having a releasing spring connected to the actuator lever, means for holding the actuator lever and the escape lever tensioned, including an element releasably engaging the machine frame, and means for releasing said element from the frame.

77. In a register, numeral wheels, and carry-tripping means including wheel-actuator levers each spring-impelled, an escape wheel for each numeral wheel, an escape lever engaging the escape wheel and carried by and having a releasing spring connected to the actuator lever, means for holding the actuator lever and the escape lever tensioned, including an intermediate lever engaging the escape lever and a latch lever fulcrumed to the intermediate lever and releasably engaging the machine frame, and means for releasing the latch lever from the frame.

78. In a register, numeral wheels, and carry-tripping means including spring-impelled wheel-actuator levers, an escape wheel for each numeral wheel, an escape lever engaging the escape wheel and carried by and having a releasing spring connected to the actuator lever, means for holding the actuator lever and the escape lever tensioned, including an intermediate lever engaging the escape lever and a latch lever fulcrumed to the intermediate lever and releasably engaging the machine frame, and means including a cam driven from a numeral wheel for releasing the latch lever from the frame.

79. In a register, numeral wheels, and carry-tripping means including an escape wheel rotatable with its related numeral wheel, an escape lever having engagement with the escape wheel and coacting therewith to also check a numeral wheel at the end of its registering movement, a lever fulcrumed to the machine frame and engaging the escape lever, and means for releasing the engagement of the levers in carrying.

80. In a register, numeral wheels, and carry-tripping means including an escape wheel rotatable with its related numeral wheel, actuator levers, an escape lever carried by each actuator lever, having engagement with the escape wheel and coacting therewith to also check the numeral wheel at the end of its registering movement, a lever fulcrumed to the machine frame and engaging the escape lever, and means for releasing the engagement of the levers in carrying.

81. In a register, numeral wheels, and carry-tripping means including an escape wheel rotatable with its related numeral wheel, an escape device engaging the escape

wheel and coacting therewith to also check a numeral wheel at the end of its registering movement, and a cam driven from a numeral wheel, and acting to release the engagement of said device in carrying.

82. In a register, numeral wheels, and carry-tripping means including an escape wheel for each numeral wheel, actuator levers, an escape device carried by each actuator lever and engaging the escape wheel and coacting therewith to also check the numeral wheel at the end of its registering movement, and a cam driven from the numeral wheel of next lower order, and acting to release the engagement of said device.

83. In a register, numeral wheels, and carry-tripping means including an escape wheel rotatable with its related numeral wheel, an escape device engaging the escape wheel and coacting therewith to also check a numeral wheel at the end of its registering movement, and a cam driven from the numeral wheel of next lower order, and acting to release the engagement of said device.

84. In a register, numeral wheels, and carry-tripping means including an escape wheel for each numeral wheel, actuator levers, an escape device carried by each actuator lever and engaging the escape wheel and coacting therewith to also check the numeral wheel at the end of its registering movement, and means for releasing the engagement of said device.

85. In a register, numeral wheels, and carry-tripping means including an escape wheel for each numeral wheel, actuator levers, an escape device carried by each actuator lever and engaging the escape wheel and coacting therewith to also check the numeral wheel at the end of its registering movement, and a cam driven from the numeral wheel of next lower order, and acting to release the engagement of said device.

86. In a register, a numeral wheel, an escape wheel therefor, an escape device movable to engage and disengage said escape wheel, and a stationary member for limiting the engaging movement of said device.

87. In a register, a numeral wheel, an escape wheel therefor, an escape device including a lever movable to engage and disengage said escape wheel, and a stationary frame member for limiting the engaging movement of said lever.

88. In a register, numeral wheels, actuators therefor including each a lever movable from normal position to carry, and means including a lever fulcrumed to the machine frame for tripping the carry and for restoring the actuator lever to normal position after a carry.

89. In a register, numeral wheels, actuators therefor including each a lever mov-

able from normal position to carry, and means including a cam driven from a numeral wheel for tripping the carry and for restoring an actuator lever to normal position after a carry.

70

90. In a register, numeral wheels, actuators therefor including each a lever movable from normal position to carry, and means including an escape device carried by each actuator lever and a member controlling said device for tripping the carry and for restoring the actuator lever to normal position after a carry.

75

91. In a register, numeral wheels, actuators therefor including each a lever movable from normal position to carry, and means including an escape lever carried by each actuator lever, an intermediate lever fulcrumed to the machine frame and engaging the escape lever, and a cam driven from a numeral wheel and operating the intermediate lever for tripping the carry and for restoring the actuator lever to normal position after a carry.

80

92. In a register, numeral wheels, carry actuators therefor including each a spring-impelled lever, and means including an escape lever carried by each actuator lever and having a releasing spring connected thereto, an intermediate lever engaging the escape lever, a latch lever fulcrumed to the intermediate lever and releasably engaging the machine frame, and a cam driven from a numeral wheel for tripping the carry and for restoring and tensioning the actuator and escape levers after a carry.

90

93. In a register, numeral wheels, actuators therefor including each a lever movable from normal position to carry, and means including a lever fulcrumed to the machine frame for checking a wheel at the end of its registering movement and for restoring the actuator lever to normal position after a carry.

105

94. In a register, numeral wheels, actuators therefor including each a lever movable from normal position to carry, and means including a cam driven from the numeral wheel of next lower order for checking the related wheel at the end of its registering movement and for restoring the actuator lever to normal position after a carry.

110

95. In a register, numeral wheels, actuators therefor including each a lever movable from normal position to carry, and means including an escape device carried by each actuator lever for checking the wheel at the end of its registering movement and for restoring the actuator lever to normal position after a carry.

120

96. In a register, numeral wheels, actuators therefor including each a lever movable from normal position to carry, and means including an escape lever carried by

125

130

- each actuator lever, an intermediate lever fulcrumed to the machine frame and engaging the escape lever, and a cam driven from the numeral wheel of next lower order 5 and controlling said intermediate lever for checking the related wheel at the end of its registering movement and for restoring the actuator lever to normal position after a carry.
- 10 97. In a register, numeral wheels, actuators therefor including each a spring-impelled lever movable from normal position to carry, and means including an escape lever carried by and having a releasing 15 spring connected to the actuator lever, an intermediate lever engaging the escape lever, and a cam driven from the numeral wheel of next lower order and controlling said intermediate lever for checking the 20 related wheel at the end of its registering movement and for restoring the actuator and escape levers to normal position and tensioning the same after a carry.
98. In a register, numeral wheels, normally tensioned carry actuators therefor, and means including a lever fulcrumed to the machine frame and controlling means for said lever for tripping the carry and for checking a wheel at the end of all register- 25 30
99. In a register, numeral wheels, normally tensioned carry actuators therefor, and means including a cam driven from a numeral wheel of lower order for tripping the carry and for checking the higher order wheel at the end of all registering movements thereof.
100. In a register, numeral wheels, actuators therefor, and means including an ele- 40 ment releasably engaging the machine frame and controlling means for said element for tripping the carry and for checking a wheel at the end of all registering movements thereof.
- 45 101. In a register, numeral wheels, normally tensioned carry actuators therefor including each a lever, and means including an escape device carried by each actuator lever and controlling means for said device 50 for tripping the carry and for checking a wheel at the end of all registering movements thereof.
102. In a register, numeral wheels, normally tensioned carry actuators therefor, 55 and means including an element releasably engaging the machine frame and a cam driven from a numeral wheel of lower order and controlling said element for tripping the carry and for checking the higher order 60 wheel at the end of all registering movements thereof.
103. In a register, numeral wheels, normally tensioned carry lever actuators therefor, and means including an escape 65 lever carried by each actuator lever, an in- termediate lever engaging the escape lever, a latch lever fulcrumed to the intermediate lever and releasably engaging the machine frame, and a cam driven from the numeral wheel of next lower order and controlling 70 said latch lever for tripping the carry and for checking the related wheel at the end of its registering movement.
104. In a register, numeral wheels normally tensioned carry lever actuators there- 75 for, and means including an escape lever carried by each actuator lever, an intermediate lever fulcrumed to the machine frame and engaging the escape lever, and a cam driven from the numeral wheel of next 80 lower order and controlling said intermediate lever for tripping the carry and for checking the related wheel at the end of its registering movement.
105. In a register, numeral wheels, spring- 85 impelled lever carry actuators therefor, and means including an escape lever carried by each actuator lever and having a releasing spring connected thereto, an intermediate lever engaging the escape lever, a latch lever 90 carried by the intermediate lever and releasably engaging the machine frame, and a cam driven from the numeral wheel of next lower order for tripping the carry and for checking the related wheel at the end of its registering 95 movement.
106. In a register, numeral wheels, spring actuators therefor including each a lever re- 100 leasable from normal position to carry, and means including a lever fulcrumed to the machine frame for tripping the carry, for restoring the actuator lever to normal position after a carry, and for checking a wheel at the end of its registering movement.
107. In a register, numeral wheels, spring actuators therefor including each a lever re- 105 leasable from normal position to carry, and means including a cam driven from the numeral wheel of next lower order for tripping the carry, for restoring the actuator lever to normal position after a carry and for checking the related wheel at the end of its registering movement.
108. In a register, numeral wheels, spring actuators therefor including each a lever re- 110 leasable from normal position to carry, and means including an escape device carried by each actuator lever and controlling means for said device for tripping the carry, for restoring the actuator lever to normal position after a carry, and for checking the wheel at the end of its registering movement.
109. In a register, numeral wheels, spring actuators therefor including each a lever re- 115 leasable from normal position to carry, and means including an escape lever carried by each actuator lever, an intermediate lever engaging the escape lever and a cam driven from the numeral wheel of next lower order and controlling said intermediate lever for 120
- 130

tripping the carry, for restoring the actuator lever to normal position after a carry and for checking the related wheel at the end of its registering movement.

5 110. In a register, numeral wheels, actuators therefor including each a spring-impelled lever releasable from normal position to carry, and means including an escape lever carried by and having a releasing

10 spring connected to each actuator lever, an intermediate lever engaging the escape lever, and a cam driven from the numeral wheel of next lower order and controlling said intermediate lever for tripping the carry, for

15 restoring the actuator and escape levers to normal position and tensioning the same after a carry, and for checking the related wheel at the end of its registering movement.

20 111. In a register, a numeral wheel, an escape wheel rotatable therewith, an escape device engaging the escape wheel and having a spring for releasing the device from the wheel, means including an element releasably engaging the machine frame for holding the spring device tensioned and in engagement with the escape wheel, and means for releasing said element from the frame in the carrying operation.

25 112. In a register, a numeral wheel, an escape wheel rotatable therewith, an escape device engaging and having a spring for releasing it from the escape wheel, means including an element releasably engaging the machine frame for holding the escape device tensioned and in engagement with the escape wheel, and means including a cam rigidly driven from the numeral wheel for releasing the holding means in the carrying

30 40 operation. 113. In a register, a numeral wheel, an escape wheel rotatable therewith, an escape lever engaging and having a spring for releasing it from the escape wheel, means including an intermediate lever engaging the escape lever and a latch lever carried by the intermediate lever and releasably engaging the machine frame for holding the escape lever tensioned and in engagement with the escape wheel, and means for releasing the holding means in the carrying operation.

45 114. In a register, a numeral wheel, an escape wheel rotatable therewith, an escape lever engaging and having a spring for releasing it from the escape wheel, means including an intermediate lever engaging the escape lever and a latch lever carried by the intermediate lever and releasably engaging the machine frame for holding the escape lever tensioned and in engagement with the escape wheel, and means including a cam driven from the numeral wheel and acting to release the latch lever from the frame and to release the holding means in the carrying

50 60 65 operation.

115. In a register, a numeral wheel, an escape wheel rotatable therewith, an escape device engaging and having a spring for releasing it from the escape wheel, means including an element releasably engaging the machine frame for holding the escape device tensioned and in engagement with the escape wheel, means for releasing said element from the frame and for releasing the holding means in the carrying operation, and means for preventing the reengagement of said element with the frame during the carrying.

70 116. In a register, a numeral wheel, an escape wheel rotatable therewith, an escape lever engaging and having a spring for releasing it from the escape wheel, means including an intermediate lever engaging the escape lever and a latch lever carried by the intermediate lever and releasably engaging the machine frame for holding the escape lever tensioned and in engagement with the escape wheel, means for releasing the holding means in the carrying operation, and means for preventing the reengagement of said latch lever with the frame during the carrying.

75 80 85 90 95 100 105 110 115 120 125 130 116. In a register, a numeral wheel, an actuator engaging and having a superior spring for rotating said wheel, an escape wheel, an escape device carried by the actuator and engaging and having an inferior spring for releasing it from the escape wheel, means for holding the escape device tensioned and in engagement with the escape wheel and for thereby holding the actuator tensioned, and means for releasing the holding means in carrying.

117. In a register, a numeral wheel, an actuator engaging and having a superior spring for rotating said wheel, an escape wheel, an escape device carried by the actuator and engaging and having an inferior spring for releasing it from the escape wheel, means for holding the escape device tensioned and in engagement with the escape wheel and for thereby holding the actuator tensioned, and means for releasing the holding means in carrying.

118. In a register, a numeral wheel, an actuator therefor including a lever having a superior spring for rotating the wheel, an escape wheel, an escape lever carried by the actuator lever and engaging and having an inferior spring for releasing it from the escape wheel, means for holding the escape lever tensioned and in engagement with the escape wheel and for thereby holding the actuator lever tensioned, and means for releasing the holding means in carrying, the actuator lever being adapted to reengage the escape lever with the escape wheel.

actuator lever having a spring for rotating the wheel, an escape wheel, an escape lever carried by the actuator lever and engaging and having a spring for releasing it from the escape wheel, means including an element releasably engaging the machine frame for holding the escape lever tensioned and in engagement with the escape wheel and for thereby holding the actuator lever tensioned, and means for releasing the holding means in carrying.

127. In a register, numeral wheels, an actuator lever having a spring for rotating a wheel, an escape wheel, an escape lever carried by the actuator lever and engaging and having a spring for releasing it from the escape wheel, means including a cam driven from the numeral wheel of next lower order for holding the escape lever tensioned and in engagement with the escape wheel and for thereby holding the actuator lever tensioned, said cam acting to release the holding means in carrying.

128. In a register, numeral wheels, an actuator lever having a spring for rotating a wheel, an escape wheel, an escape lever carried by the actuator lever and engaging and having a spring for releasing it from the escape wheel, means including an intermediate lever engaging the escape lever and a cam driven from the numeral wheel of next lower order for holding the escape lever tensioned and in engagement with the escape wheel and for thereby holding the actuator lever tensioned, said cam acting to release the holding means in the carrying operation.

129. In a register, numeral wheels, an actuator lever having a spring for rotating a wheel, an escape wheel, an escape device carried by the actuator lever and engaging and having a spring for releasing it from the escape wheel, means including an element releasably engaging the machine frame for holding the escape device tensioned and in engagement with the escape wheel and for thereby holding the actuator lever tensioned, and means including a cam driven from the numeral wheel of next lower order for releasing the holding means in the carrying operation.

130. In a register, a numeral wheel, an actuator lever having a spring for rotating the wheel, an escape wheel, an escape device carried by the actuator lever and engaging and having a spring for releasing it from the escape wheel, means including an intermediate lever engaging the escape device and a latch lever carried by the intermediate lever and releasably engaging the machine frame for holding the escape device tensioned and in engagement with the escape wheel and for thereby holding the actuator lever tensioned, and means for releasing the holding means in the carrying operation.

131. In a register, numeral wheels, an actuator lever having a spring for rotating a wheel, an escape wheel, an escape lever carried by the actuator lever and engaging and having a spring for releasing it from the escape wheel, means including an intermediate lever engaging the escape lever and a latch carried by the intermediate lever and releasably engaging the machine frame for holding the escape lever tensioned and in engagement with the escape wheel and for thereby holding the actuator lever tensioned, and a cam driven from the numeral wheel of next lower order for releasing the holding means in the carrying operation.

132. In a register, a numeral wheel, an actuator lever having a spring for rotating the wheel, an escape wheel, an escape lever carried by the actuator lever and engaging and having a spring for releasing it from the escape wheel, means including an element releasably engaging the machine frame for holding the escape lever tensioned and in engagement with the escape wheel and for holding the actuator lever tensioned, means for releasing the holding means in the carrying operation, and means for preventing reengagement of said element with the frame during the carrying operation.

133. In a register, a numeral wheel, an actuator lever having a spring for rotating the wheel, an escape wheel, an escape lever carried by the actuator lever and engaging and having a spring for releasing it from the escape wheel, means including an intermediate lever engaging the escape lever and a latch lever carried by the intermediate lever and releasably engaging the machine frame for holding the escape lever tensioned and in engagement with the escape wheel and for holding the actuator lever tensioned, and means for preventing reengagement of the latch lever with the frame during the carrying.

134. In a register, a numeral wheel, an actuator lever therefor having a spring for rotating the wheel, an escape wheel, an escape lever carried by the actuator lever and engaging and having a spring for releasing it from the escape wheel, means for holding the escape lever tensioned and in engagement with the escape wheel and for thereby holding the actuator lever tensioned, and means for releasing the holding means in the carrying operation, said holding means co-operating with the actuator lever to retension the escape lever and to re-engage it with the escape wheel prior to a carry, to thereby hold the actuator lever tensioned.

135. In a register, a numeral wheel, an actuator lever therefor having a spring for rotating the wheel, an escape wheel, an escape lever carried by the actuator lever and engaging and having a spring for re-

- leasing it from the escape wheel, means for holding the escape lever tensioned and in engagement with the escape wheel, including an intermediate lever engaging the escape lever and a latch lever carried by the intermediate lever and releasably engaging the machine frame, and means for releasing the holding means in the carrying operation, said holding means coöperating with the actuator lever to retension the escape lever and to reengage it with the escape wheel prior to a carry, to thereby hold the actuator lever tensioned.
136. In a register, a numeral wheel, a column actuator, a series of digital keys for said actuator, and denominational stop devices for arresting the actuator and including each a lever the opposite arms of which are engaged by different digital keys.
137. In a register, a numeral wheel, a column actuator, a series of digital keys for

said actuator, and denominational stop devices for arresting the actuator and including each a lever the opposite arms of which engage the actuator upon operation by different digital keys.

138. In a register, a numeral wheel, a column actuator, a series of digital keys for said actuator, and denominational stop devices for arresting the actuator and including each a lever one arm of which engages the actuator upon operation by one digital key and both arms of which engage the actuator upon operation by another digital key.

In testimony whereof I affix my signature in presence of two witnesses.

GEORGE C. CHASE.
